Primary Examiner — Jae Liang*Assistant Examiner* — Bryan C Gusman(57) CLAIM

The ornamental design for a combined desk and office cabinet, as shown and described.

DESCRIPTION

FIG. 1 is an upper perspective view of a combined desk and office cabinet showing my new design;

FIG. 2 is a lower perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is another perspective view of the combined desk and office cabinet of FIG. 1, shown in an alternate configuration. The dash-dot broken lines in the drawings depict portions of the combined desk and office cabinet that form no part of the claimed design.
